ATTORNEY

UNITED STATES PATENT OFFICE

JOHN W. LITTLE, OF PAWTUCKET, RHODE ISLAND

END LABEL FOR TUBULAR CLOTH ROLLS

Application filed October 8, 1926. Serial No. 140,224.

The present invention relates to improvements in end labels for tubular supporting rolls for cloth, or the like, and has for an object to provide a foldable label adapted to be engaged in the tube end in a manner to close the end of such tube, and at the same time provide an attractive label and finish for the roll of cloth wound on the tube.

Another object is to provide a label which 10 may be readily inserted and removed, will be self-centering within the tube, and will be reliably held, through frictional engagement with the inner surface of the tube, against accidental turning, displacement, or disengagement. To this end, it is proposed to provide securing flaps adapted to be inserted in the tube under tension, and which when inserted will exert transverse pressure to frictionally engage the longitudinal edges of 15 the flaps with the inner surface of the tube. It is particularly proposed, in the present embodiment, to provide a structure in which the flaps are engaged with the tube surface along the entire lengths of their longitudinal 20 edges, and upon intersecting helical lines, out of parallel relation with the axis of the tube and its plane of rotation, so that a substantial frictional holding pressure is exerted to resist turning, displacement, or disengaging movement longitudinally of the tube axis.

A further object is to provide a label device, including a label portion, preferably in the form of a disk, which may be printed before assembly, and a card-board attaching 35 portion, secured to said label portion and hinged relatively thereto, so that it may be flattened into parallel relation to the label portion to facilitate packing and shipping.

With the above and other objects in view, 40 embodiments of the invention are shown in the accompanying drawings, and these embodiments will be hereinafter more fully described with reference thereto, and the invention will be finally pointed out in the 45 claims.

In the drawings:—

Fig. 1 is a perspective view showing a tube with cloth rolled thereon, and provided with end label devices, according to the present 50 embodiment of the invention;

Fig. 2 is a perspective view of one end of the tube, and showing the label device in position to be inserted;

Fig. 3 is a view, half in side elevation, and half in longitudinal section, showing the 55 tube with label devices at each end;

Fig. 4 is a sectional view, taken along the line 4—4 of Fig. 3;

Fig. 5 is a rear plan view of the label device in flattened relation;

Fig. 6 is an edge view thereof; and

Fig. 7 is a side elevation showing a tube provided with a slightly modified form of the invention.

Referring to the drawings, the tube 10, of 65 heavy pasteboard, or the like, is adapted to have cloth or other material wound thereon, as shown in Fig. 1, and a label device, according to my invention is inserted and retained at each end thereof. The label device, 70 according to the present embodiment of the invention, comprises a disk 11, of card-board or the like, adapted to have advertising or other matter printed directly on its face, or applied by a label pasted thereon, and to the 75 rearward side of which the attaching flap member is secured.

The flap member is preferably blanked out as a single flat piece of card-board, and includes a central portion 12 of rectangular 80 form and flap portions 13 extending at opposite sides and having their longitudinal edges 14 diverging from said portion 12 to their outer ends. Score lines 15 are provided between the portion 12 and said flap portions, 85 about which the latter are adapted to have hinged movement relatively to the portion 12, and centrally at the outer ends of the flap portions there are provided longitudinal score lines 16, about which the outer ends are 90 adapted to be bent or flexed into transverse angular relation. As shown in Figs. 5 and 6, the score lines are at the inner surface, the folding of the member being inwardly with respect to said surface. The flap member is 95 secured to the rearward surface of the disk portion 11 by pasting, or it may be stapled, or otherwise suitably secured. The relatively large surface of the flap member may have advertising, descriptive, or other matter related 100

tive to the goods, printed or otherwise applied thereon.

The disk 11 may be of a diameter adapted only to cover the end of the tube, or it may be of greater diameter, and the flap member is proportioned to the inner diameter of the particular sized tube to which the device is applied. As clearly shown in Fig. 4, the rectangular portion 12 is of a size that in the inserted relation its several corners engage the inner surface of the tube, while the outer ends of the flap portions are of a width greater than the inner diameter of the tube, and upon being compressed transversely into angular relation abut each other at their corners contiguous to the tube surface and press the side edges 14 outwardly into frictional engagement with said tube surface. The edges 14 are so designed that in the engaged relation they have frictional engagement along their entire lengths along substantially helical lines, the lines of engagement of the respective flaps converging at each side. The label device is thus centered and frictionally held in its inserted position, the frictional engagement of the edges 14 along converging helical lines not only resisting outward pull on the device, but opposing turning thereof in the tube equally in either direction.

The convenience with which the device may be inserted and removed permits the roll of cloth to be readily placed upon a mandrel, when desired, for winding off cloth, and also facilitates the marking of the label and the reading of any descriptive or other matter that may be applied to the flap member.

In Fig. 7 there is illustrated a modification, in which the disk 11^a is of relatively large diameter and may serve as a reel or spool end, or to conceal uneven winding of the cloth. The flap member, in this embodiment, is secured by staples 17, and a label 18 is preferably pasted upon the face of the disk to conceal the staples.

I have illustrated and described preferred and satisfactory embodiments of the invention, but it will be obvious that changes may be made therein, within the spirit and scope thereof, as defined in the appended claims.

Having thus described my invention, what I claim and desire to secure by Letters Patent is:—

1. A label device for cylindrical tubular supports for cloth or the like, comprising a flat label member adapted to engage and close a tube end, and retaining means at the rear side of said member including a pair of flat relatively wide flap portions hinged with respect to said flat label member along spaced and parallel elongated hinge lines, said flap portions adapted to be inserted in the tube to retain said label member with respect to said tube end, the longitudinal edges of said flap portions constituting spaced frictional

engaging surfaces, said spaced hinges adapted to cooperate to rigidly support said label member with respect to said flap portions.

2. A label device for tubular supports for cloth or the like, comprising a label member adapted to engage and close a tube end, and retaining means at the rear side of said member including a pair of flaps hingedly connected to said member along spaced parallel lines, said hinged ends being of a width adapted to engage the inner surface of the tube, said flaps increasing in width toward their ends and adapted to be flexed transversely to frictionally engage within the tube to retain said label member with respect to said tube end.

3. A label device for tubular supports for cloth or the like, comprising a label member adapted to engage and close a tube end, and retaining means at the rear side of said member including a pair of flaps hingedly connected to said member along spaced parallel lines, said hinged ends being of a width adapted to engage the inner surface of the tube, said flaps increasing in width toward their ends and adapted to be flexed transversely to frictionally engage within the tube, the edges of said flap being so formed as to engage along converging helical lines at each side to retain said label member with respect to the tube end.

4. A label device for tubular supports for cloth or the like, comprising a label member adapted to engage and close a tube end, and retaining means at the rear side of said member including a flat attaching portion secured to said member and a pair of flat relatively wide flap portions hinged with respect to said flat portion along spaced and parallel elongated hinge lines, said flap portions adapted to be inserted in the tube to retain said label member with respect to said tube end, the two longitudinal edges of each of said flap portions constituting spaced frictional engaging surfaces, said spaced hinges adapted to cooperate to rigidly support said label member with respect to said flap portion.

5. A label device or tubular supports for cloth or the like, comprising a label member adapted to engage and close a tube end, and retaining means at the rear side of said member consisting of a flat piece of card-board or the like, including a central attaching portion secured to said label member and oppositely extending flat relatively wide flap portions adapted to have hinged movement with respect to said attaching portion along spaced and parallel elongated axes, said flap portions adapted to be inserted in the tube to retain said label member with respect to said tube end, the two longitudinal edges of each of said flap portions constituting spaced frictional engaging surfaces, said spaced hinges

adapted to cooperate to rigidly support said label member with respect to said flap portion.

Signed at Pawtucket, in the county of Providence, and State of Rhode Island, this
5 23rd day of September, 1926.
